VAULT WALL CONSTRUCTION

Palmer Bescherer, York, Pa., assignor to Diebold,
Incorporated, Canton, Ohio, a corporation of
Ohio

Application September 27, 1946, Serial No. 699,770

20 Claims. (Cl. 109—83)

1

The invention relates to vault wall construction and more particularly to a reinforcing arrangement or structure for the concrete walls of a vault which strengthens the concrete walls, effectively resists penetration by burglar tools, and resists bomb shock waves.

Vault walls in the past invariably have been constructed of reinforced concrete for rendering the interior of the vault fire-proof and burglar-proof. Numerous kinds or types of reinforcement have been used in concrete vault walls in an attempt to provide a wall construction satisfactory from every standpoint.

Such reinforcement has included wire mesh, latticed metal, metal lath-like material, spiral wire coils, twisted and interlaced rods, staggered metal discs, corrugated plates, angled reinforcing bars, bar joists, H-beams, steel rails, irregularly shaped bars, and various combinations of such materials. Underwriter's requirements provide that a reinforced concrete vault wall should contain at least 27 pounds of metal reinforcement per square foot of projected vault wall area.

It is known, from many standpoints, that a so-called basket weave construction and arrangement for the reinforcement is the most desirable arrangement, provided that the metal is dispersed substantially throughout the vault wall thickness and is not concentrated in any one plane or narrow zone. It also is known that a regular arrangement of the parts of the reinforcing members as viewed when projected to a wall surface is undesirable.

I have discovered a new construction of rod A-frame reinforcing member which avoids the enumerated prior art difficulties and solves the existing problem in a satisfactory manner such that an irregular wire basket weave reinforcement arrangement is dispersed throughout the major portion of the concrete vault wall with a minimum amount of metal providing a maximum amount of reinforcing strength, burglar tool penetration resistance, and resistance to bomb shock waves.

Accordingly, it is a primary object of the present invention to improve and simplify the construction of reinforced concrete vault walls.

It is a further object of the present invention to provide a new concrete vault wall reinforcement construction which has maximum reinforcing, burglary resisting, and bomb shock resisting characteristics with a minimum amount of metal embedded in the concrete.

Furthermore, it is an object of the present invention to provide a new concrete vault wall re-

2

inforcement construction having an irregularly dispersed basket weave arrangement involving substantially only the minimum required amount of metal, namely, 27 pounds of metal per square foot of projected wall surface.

Moreover, it is an object of the present invention to provide an improved reinforced concrete vault wall construction which has a comparatively low fabrication cost in that the metal reinforcing members may be made in substantially complete and finished form by production methods at the place of fabrication.

Furthermore, it is an object of the present invention to provide a reinforcement construction for reinforced concrete vault walls which nests and is therefore compact for bundling and shipping from the place of fabrication to the place of installation.

Also, it is an object of the present invention to provide a concrete vault wall reinforcement construction which is quick and easy to erect by inexperienced labor and is self-sustaining when erected thereby eliminating collateral erection difficulties.

Furthermore, it is an object of the present invention to provide a concrete vault wall reinforcement construction which does not require wiring or wire tying for erecting the reinforcement.

Also, it is an object of the present invention to provide an improved vault wall reinforcing member construction which nests during installation and is thereby automatically spaced from adjacent reinforcing members without the provision of spacing means.

Likewise, it is an object of the present invention to provide a new concrete vault wall reinforcement construction which is very rigid when erected and which includes members tied or locked to adjacent similar members by the simple insertion of straight lock rods at infrequent intervals.

Furthermore, it is an object of the present invention to provide a new reinforcement construction for concrete vault walls which may be erected before the concrete wall forms are erected and around which the concrete wall forms may then be readily erected.

Also, it is an object of the present invention to provide an improved concrete vault wall reinforcement construction permitting quick pouring and easy flow within the concrete forms, through and around the reinforcement, to obtain a true and efficient monolithic structure.

Furthermore, it is an object of the present in-

vention to provide a new concrete vault wall steel reinforcement construction which confines shock area in the steel to a small space.

Moreover, it is an object of the present invention to provide a new rod reinforcement for concrete vault wall construction which, with a minimum amount of metal, provides most efficient concrete reinforcing and strengthening characteristics, with reinforcing rods running in vertical, horizontal, cross-wise, and angular directions, dispersed throughout a major portion of the concrete wall thickness.

Likewise, it is an object of the present invention to provide a new concrete vault wall reinforcement construction having reinforcing rods efficiently arranged with a minimum amount of metal to inhibit or interrupt the penetration of burglar tools such as drilling or arc torch cutting.

Finally, it is an object of the present invention to provide a new reinforced concrete vault wall construction which is easy to manufacture and erect, which is highly resistant to burglary and shock, which is inexpensive, which overcomes the foregoing prior art difficulties, which solves long-standing problems in the art, and which obtains the many new results and advantages herein set forth.

These and other objects and advantages apparent to those skilled in the art from the following description may be obtained, the stated results achieved, and the described difficulties overcome, by the devices, constructions, arrangements, combinations, sub-combinations, parts, elements, discoveries and principles which comprise the present invention, the nature of which is set forth in the following general statement, a preferred embodiment of which—illustrative of the best mode in which applicant has contemplated applying the principle—is set forth in the following description and shown in the drawings, and which are particularly and distinctly pointed out and set forth in the appended claims forming part hereof.

The nature of the improvements in vault wall construction of the present invention may be stated in general terms as preferably including in a reinforced vault wall, a reinforcing structure including A-frame members, each A-frame member comprising longitudinal rod members spaced apart and connected together by generally A-shaped cross rod members; each cross rod member being formed with V-shaped central leg portions and out-turned aligned leg portions terminating in parallel leg portions which in turn terminate in preferably angularly hooked portions, said cross rod members each being joined as by welding at the V-apices with one longitudinal rod member and also being joined as by welding at a plurality of spaced places along the aligned out-turned leg portions with a plurality of other longitudinal rod members; said A-frame members thus constructed nesting within one another when placed side by side for shipment and erection; said A-frame members when nested having the hooked portions of the cross rod members of one A-frame member engaging certain longitudinal rods of the next adjacent A-frame member; modified corner and butt frame members similar to said A-frame members for forming a complete reinforcing panel structure; lock rods inserted at intervals engaging the V-attached longitudinal rod of one A-frame member and also engaging the aligned-leg-attached longitudinal rods of another A-frame member for locking a plurality of nested A-frame members together; each A-frame

member being adapted to stand end-wise on a flat surface, and the assembled nested and locked A-frame members forming a rigid, stable panel structure; there being one such panel structure at each of the bottom, side and roof walls of the vault; and concrete poured in and around each such panel structure to form a reinforced concrete wall vault.

By way of example, a preferred embodiment of the improved vault wall construction is illustrated in the accompanying drawing forming part hereof wherein:

Fig. 1 is a sectional plan view of four side walls and the bottom wall of a vault provided with the improved reinforcing construction;

Fig. 2 is a fragmentary sectional view of a bottom corner of the vault walls of Fig. 1 illustrating the reinforcement for the bottom wall of the vault, looking in the direction of the arrows 2—2, Fig. 1;

Fig. 3 is a perspective view of a fragmentary portion of one of the improved A-frame members;

Fig. 4 is a top end view of the A-frame member shown in Fig. 3;

Fig. 5 is a side elevation of the A-frame member illustrated in Fig. 4 with another similar A-frame member nested thereagainst;

Fig. 6 is a view similar to Fig. 4 of a modified A-frame member used as a corner frame;

Fig. 7 is a view similar to Figs. 4 and 6 of another modified form of frame member used as a butt frame;

Fig. 8 is a perspective view of a panel locking clip; and

Fig. 9 is a perspective view of a lock rod.

Similar numerals refer to similar parts throughout the various figures of the drawings.

The improved vault wall reinforcement construction illustrated in Figs. 1 and 2 is based upon and composed primarily and principally of a new rod A-frame member generally indicated at 1 and best shown in Figs. 3, 4 and 5. Each A-frame member 1 is composed of a plurality of longitudinal rods 2, 3, 4, 5 and 6. The longitudinal rods 2, 3, 4, 5 and 6 are joined together in spaced-apart relation at spaced intervals by generally A-shaped cross rod members 7. Each cross rod member 7 has a V-shaped central portion formed by legs 8 and 9 diverging from an apex 10. The legs 8 and 9 are bent, respectively, at 11 and 12, and extend in out-turned aligned leg portions 13 and 14, respectively. The leg portions 13 and 14 are bent at right angles at the corners 15 and 16 to form parallel leg portions 17 and 18, respectively. The parallel leg portions 17 and 18 terminate in in-turned angled hooked portions 19 and 20, respectively.

The longitudinal rods 2, 3, 4, 5 and 6 are joined to a plurality of cross rod members 7 in any desired manner preferably by any desired or convenient type of welding to form the A-frame member 1 illustrated in Figs. 3 and 4. In forming the A-frame member 1, a longitudinal rod 6 is welded at spaced intervals to the apices 10 of a plurality of cross rods 7; the longitudinal rod 2 is welded at the corner 15 between the leg portions 13 and 17 of each cross rod 7; the longitudinal rod 5 is welded to the similar corner 16 between the leg portions 14 and 18 of each cross rod 7; the longitudinal rod 3 is welded substantially opposite the corner 11 between the leg portions 8 and 13 of each cross rod 7; and the longitudinal rod 4 is similarly welded substantially opposite the corner 12 between leg portions 9 and 14 of each cross rod 7. In the drawings, tack

welds are shown at the joints between longitudinal and cross rods, but any type of welding may be used for forming the joints.

Thus, the axes of the longitudinal rods 2, 3, 4 and 5 all preferably lie in the same plane, since they are each welded to one side surface of the aligned leg portions 13 and 14 of the cross rods 7. The axis of the longitudinal rod 6 is located in a plane parallel to the plane of the longitudinal rods 2, 3, 4 and 5, and spaced therefrom a distance approximately twice the length of the parallel leg portions 17 and 18, for a purpose to be later described.

For production convenience, the cross rods 7 may be spaced evenly apart along the length of the longitudinal rods 2, 3, 4, 5 and 6, although uniformity of spacing is not necessarily required.

In Fig. 5, two A-frame members 1 are shown assembled or nested together, and, for convenience in description, certain parts of one member 1 are indicated by the numerals 1, 5, 6, 7, 9, 10, 16, 18 and 20 and the similar parts of the other member 1' are indicated by the numerals 1', 5', 6', 7', 9', 10', 16', 18', and 20'. Also for convenience the member 1' is illustrated in dot-dash lines in Fig. 4.

Thus, rod 6' of the A-frame member 1' lies within the space formed between V-legs 8 and 9 of cross rod members 7 of the A-frame member 1; and the rods 2' and 5' of the A-frame member 1' are engaged, respectively, by hooks 19 and 20 of the cross rod members 7 of the A-frame member 1. This inter-engaging, nesting of the A-frame members 1 is repeated when a plurality of A-frame members 1 are nested together to form a wall reinforcement panel, as illustrated in Fig. 1 at A.

In order to complete the formation of the wall panel reinforcing structure A, it is necessary to provide a corner frame member 21 illustrated in Fig. 6 and a butt frame member 22 illustrated in Fig. 7. The corner frame member 21 is generally similar in shape and construction to the A-frame member 1 excepting that the V-leg members thereof are shortened and additional longitudinal rods 23 and angled cross rod portions 24 are provided to form box-like corners.

The butt frame member 22 is also generally similar in construction to the A-frame member 1 excepting that additional smaller V-cross rod members 25 are provided, additional longitudinal rods 26 are provided, the parallel leg portions 17 and 18 and the inward hooked portions 19 and 20 are omitted, and the aligned legs 13 and 14 are connected and formed in one piece as by rods 27.

As previously stated, when a plurality of A-frame members 1 are nested together and are closed at one end with a corner frame member 21 and at the other end with a butt frame member 22, a wall reinforcement panel is formed as indicated at A in Fig. 1.

The frame members 1, 21 and 22 may be locked together by the insertion at desired intervals of cross lock rods 28, illustrated in Fig. 9, and shown inserted in locked position in Figs. 1 and 2.

The purpose of the spacing between rod 6 and rods 2, 3, 4 and 5 of each A-frame member 1 may now be explained. Viewing Fig. 1, a lock rod 28 inserted transversely of the panel A engages to the left of the longitudinal rod 6 of one A-frame member 1 and to the right of the longitudinal rods 2, 3, 4 and 5 of the second A-frame member to the right thereby securely locking said two A-frame members together and likewise locking the intervening A-frame member 1. A very few lock

rods 28 therefore securely tie and lock all of the frame members 1, 21 and 22 together to form a wall reinforcement panel A. Other wall reinforcing panels B, C and D may be similarly provided and similarly assembled; and the panels A, B, C and D may be joined together by split locking rings 29 illustrated in Fig. 8 and shown in assembled relation in Fig. 1.

Referring to Figs. 4, 5, 6 and 7, each frame member 1, 21 and 22 will stand on end, on the ends of the longitudinal rods 2, 3, 4, 5 and 6. Furthermore, when a panel A, B, C, or D is assembled it is a stable rigid interlocked structure.

Referring to Fig. 2, a similar reinforcing panel E may be used to reinforce the base or floor slab of the vault, and a sixth similar reinforcing panel, not shown, may be used for reinforcing the roof slab of the vault.

In constructing a vault, the procedure is simple and easy. The bottom and side forms for the floor slab indicated by the lines 30 and 31 are erected, the reinforcing panel E is assembled and laid within said forms in the proper spaced relation therefrom, and the concrete floor slab is then poured. Dowels are provided which extend upward from the floor slab for tying the same to the side walls.

The inner forms for the side walls are then erected as indicated by the solid line square 32 in Fig. 1, the wall reinforcing panels A, B, C and D are erected as described, then the outer forms indicated by the solid line square 33 are erected, after which the concrete for the side walls may be poured and the top surfacing concrete for the floor slab may be finished as indicated by the line 34 in Fig. 2. The vault roof slab may then be erected in a similar manner, it being understood that a necessary opening is provided in one of the walls for erecting the vault door for access to the vault.

The diameter of the rods from which the frame members 1, 21 and 22 are formed, and the vertical spacing of the A-shaped cross rods 7 will vary according to the weight of steel per square foot of projected wall surface that is desired. It is possible, by varying said diameters and spacing, to provide a minimum of 27 pounds of steel per square foot of projected wall surface or any additional amount of steel, said 27 pounds being the minimum required by underwriter's specifications. The reinforcing rods (Figs. 1 and 2) are dispersed throughout the major portion of the thickness of the vault walls and run in substantially all directions so as to prevent penetration of burglary tools. Likewise, the reinforcing rods present the desired basket weave arrangement which has been found most efficient for concrete vault wall reinforcement, yet the basic A-frame member has a relatively simple construction which may be made at a low cost in a factory by production methods.

The frame members likewise are compact for bundling and shipping and may be quickly and easily erected by inexperienced labor without requiring wire tying. The arrangement of the reinforcing construction does not interfere with the easy erection of the concrete forms, the reinforcement panels are stable and rigid, and the basket weave and dispersed rod arrangement permit quick pouring and easy flow of the concrete.

Likewise, since each metal rod part of the reinforcing construction is of small volume and is spaced from adjacent rod parts, only a small amount of metal is located in any one region of the wall subject to shock vibration as a result of

bombing. Therefore, the shock area is confined to small spaces and the vault wall is extremely resistant to bomb shock.

Accordingly, the improved vault wall construction of the present invention eliminates prior art difficulties, solves complicated problems which have existed in the art, obtains new results, and provides for accomplishing each of the foregoing objects in a simple and reliable manner.

In the foregoing description, certain terms have been used for brevity, clearness and understanding; but no unnecessary limitations are to be implied therefrom beyond the requirements of the prior art because such words are utilized for descriptive purposes herein and not for the purpose of limitation and are intended to be broadly construed.

Moreover, the embodiment of the improved construction illustrated and described is by way of example; and the scope of the present invention is not limited to the exact details of construction of the various parts.

Having now described the features of the invention, the construction of the members thereof, the erection of a preferred embodiment of improved reinforced vault wall, and the advantageous, new and useful results obtained thereby; the new and useful devices, constructions, arrangements, combinations, sub-combinations, parts, elements, discoveries and principles, and reasonable mechanical equivalents obvious to those skilled in the art, are set forth in the appended claims.

I claim:

1. In a vault structure, a concrete wall, and a reinforcing structure embedded in said concrete wall including a plurality of A-frame members, each A-frame member comprising generally A-shaped cross rod members and spaced apart longitudinal rod members, said cross rod members being connected at spaced intervals with said longitudinal rod members, and means on the cross rod members of one A-frame member engaging certain longitudinal rods of the next adjacent A-frame member when a plurality of A-frame members are nested together to form said reinforcing structure.

2. In a vault structure, a concrete wall, and a reinforcing structure embedded in said concrete wall including a plurality of A-frame members, each A-frame member comprising generally A-shaped cross rod members and spaced apart longitudinal rod members, said cross rod members being connected at spaced intervals with said longitudinal rod members, means on the cross rod members of one A-frame member engaging certain longitudinal rods of the next adjacent A-frame member when a plurality of A-frame members are nested together to form said reinforcing structure, and lock rod means engaging longitudinal rod members of at least two A-frame members when nested together to lock said A-frame members and form a reinforcing structure panel.

3. In a vault structure, a concrete wall, and a reinforcing structure embedded in said concrete wall including a plurality of A-frame members, each A-frame member comprising generally A-shaped cross rod members and spaced apart longitudinal rod members, said cross rod members being connected at spaced intervals with said longitudinal rod members, and hooked portions on the cross rod members of one A-frame member engaging certain longitudinal rods of the next adjacent A-frame member when a plurality of

A-frame members are nested together to form said reinforcing structure.

4. In a vault structure, a concrete wall, and a reinforcing structure embedded in said concrete wall including a plurality of A-frame members, each A-frame member comprising generally A-shaped cross rod members and spaced apart longitudinal rod members, said cross rod members being formed with a series of bends, said cross rod members being connected at said bends at spaced intervals with said longitudinal rod members, and means on the cross rod members of one A-frame member engaging certain longitudinal rods of the next adjacent A-frame member when a plurality of A-frame members are nested together to form said reinforcing structure.

5. In a vault structure, a concrete wall, and a reinforcing structure embedded in said concrete wall including a plurality of A-frame members, each A-frame member comprising generally A-shaped cross rod members and spaced apart longitudinal rod members, each cross rod member being formed with aligned leg portions, said cross rod members being connected at spaced intervals with said longitudinal rod members, the connections between said longitudinal rod members and each cross rod member being at spaced apart intervals along said aligned leg portions whereby the axes of said longitudinal rod members lie in the same plane, and means on the cross rod members of one A-frame member engaging certain longitudinal rods of the next adjacent A-frame member when a plurality of A-frame members are nested together to form said reinforcing structure.

6. In a vault structure, a concrete wall, and a reinforcing structure embedded in said concrete wall including a plurality of A-frame members, each A-frame member comprising generally A-shaped cross rod members and spaced apart longitudinal rod members, each cross rod member being formed with an apex and with aligned leg portions spaced from said apex, said cross rod members being connected at spaced intervals with said longitudinal rod members, one longitudinal rod being connected to each cross rod member at the apex of the latter and the connections between other longitudinal rod members and each cross rod member being at spaced apart intervals along said aligned leg portions, and means on the cross rod members of one A-frame member engaging certain longitudinal rods of the next adjacent A-frame member when a plurality of A-frame members are nested together to form said reinforcing structure.

7. In a vault structure, a concrete wall, and a reinforcing structure embedded in said concrete wall including a plurality of A-frame members, each A-frame member comprising generally A-shaped cross rod members and spaced apart longitudinal rod members, said cross rod members being connected at spaced intervals with said longitudinal rod members, means on the cross rod members of one A-frame member engaging certain longitudinal rods of the next adjacent A-frame member when a plurality of A-frame members are nested together to form said reinforcing structure, and welded joint connections between the cross rod members and longitudinal rod members of each A-frame member.

8. In a vault structure, a concrete wall, and a reinforcing structure embedded in said concrete wall including a plurality of A-frame members, each A-frame member comprising a plurality of generally A-shaped cross rod members and a plurality

rality of longitudinal rod members, each cross rod member being formed with an apex from which central V-shaped leg portions extend terminating at bends with out-turned aligned leg portions which terminate at bends with parallel leg portions which terminate in hook means, said cross rod members being connected at spaced intervals with said longitudinal rod members, the connections between certain longitudinal rod members and each cross rod member being at spaced apart intervals along said aligned leg portions, and the hook means on the cross rod members of one A-frame member engaging certain longitudinal rods of the next adjacent A-frame member when a plurality of A-frame members are nested together to form said reinforcing structure.

9. In a vault structure, a concrete wall, and a reinforcing structure embedded in said concrete wall including a plurality of A-frame members, each A-frame member comprising a plurality of generally A-shaped cross rod members and a plurality of longitudinal rod members, each cross rod member being formed with an apex from which central V-shaped leg portions extend terminating at bends with out-turned aligned leg portions which terminate at bends with parallel leg portions which terminate in hook means, a plurality of said cross rod members being connected at their apices to one longitudinal rod member, a plurality of longitudinal rods being connected with each cross rod member at spaced intervals along said aligned leg portions, and the hook means on the cross rod members of one A-frame member engaging certain longitudinal rods of the next adjacent A-frame member when a plurality of A-frame members are nested together to form said reinforcing structure.

10. In a vault structure, a concrete wall, and a reinforcing structure embedded in said concrete wall including a plurality of A-frame members, each A-frame member comprising a plurality of generally A-shaped cross rod members and a plurality of longitudinal rod members, each cross rod member being formed with an apex from which central V-shaped leg portions extend terminating at bends with out-turned aligned leg portions which terminate at bends with parallel leg portions which terminate in hook means, a plurality of said cross rod members being connected at their apices to one longitudinal rod member, a plurality of longitudinal rods being connected with each cross rod member at spaced intervals along said aligned leg portions, the hook means on the cross rod members of one A-frame member engaging certain longitudinal rods of the next adjacent A-frame member when a plurality of A-frame members are nested together to form said reinforcing structure, and lock rods engaging the apex-connected longitudinal rod of one A-frame member and engaging certain aligned-leg-connected longitudinal rods of another A-frame member for locking a plurality of A-frame members together when nested to form a reinforcing panel structure.

11. In a vault structure, a concrete wall, and a reinforcing structure embedded in said concrete wall including a plurality of A-frame members, each A-frame member comprising generally A-shaped cross rod members and spaced apart longitudinal rod members, each cross rod member being formed with a central apex from which V-shaped central leg portions extend terminating at bends in out-turned aligned leg portions terminating at bends in parallel leg portions ter-

minating in angularly hooked portions; said cross rod members being connected at spaced intervals at their apices with one longitudinal rod, at the bends between central and out-turned leg portions with second and third longitudinal rods, and at the bends between out-turned and parallel leg portions with fourth and fifth longitudinal rods; and the hooked portions on the cross rod members of one A-frame member engaging the fourth and fifth longitudinal rods of the next adjacent A-frame member when a plurality of A-frame members are nested together to form said reinforcing structure.

12. In a vault structure, a concrete wall, and a reinforcing structure embedded in said concrete wall including a plurality of A-frame members, each A-frame member comprising generally A-shaped cross rod members and spaced apart longitudinal rod members, each cross rod member being formed with a central apex from which V-shaped central leg portions extend terminating at bends in out-turned aligned leg portions terminating at bends in parallel leg portions terminating in angularly hooked portions; said cross rod members being connected at spaced intervals at their apices with one longitudinal rod, at the bends between central and out-turned leg portions with second and third longitudinal rods, and at the bends between out-turned and parallel leg portions with fourth and fifth longitudinal rods; the hooked portions on the cross rod members of one A-frame member engaging the fourth and fifth longitudinal rods of the next adjacent A-frame member when a plurality of A-frame members are nested together to form said reinforcing structure; and lock rods engaging the first longitudinal rod member of one A-frame member and the second, third, fourth and fifth longitudinal rods of the second adjacent A-frame member when a plurality of A-frame members are nested together to lock said nested A-frame members and form a rigid, stable, reinforcing panel structure.

13. In a vault structure, a concrete wall, and a reinforcing panel embedded in said concrete wall including a plurality of A-frame members, each A-frame member comprising generally A-shaped cross rod members and spaced apart longitudinal rod members, said cross rod members being connected at spaced intervals with said longitudinal rod members, means on the cross rod members of one A-frame member engaging certain longitudinal rods of the next adjacent A-frame member when a plurality of A-frame members are nested together, a butt frame member, a corner frame member, said butt and corner frame members comprising cross rod members and longitudinal rod members connected together in spaced relation, means on the cross rod members of the corner frame member engaging certain longitudinal rods of the next adjacent A-frame member when a corner frame member is nested therewith, means on the cross rod members of one A-frame member engaging certain longitudinal rods of the butt frame member when a butt frame member is nested with a plurality of A-frame members, and lock rod means locking said A-frame, butt frame, and corner frame members together to form a reinforcing panel structure.

14. In a vault structure, concrete walls, and a reinforcing panel structure embedded in each concrete wall, each panel structure including a plurality of A-frame members, each A-frame member comprising generally A-shaped cross rod members and spaced apart longitudinal rod mem-

bers, said cross rod members being connected at spaced intervals with said longitudinal rod members, means on the cross rod members of one A-frame member engaging certain longitudinal rods of the next adjacent A-frame member when a plurality of A-frame members are nested together, lock rod means engaging longitudinal rod members of at least two A-frame members when nested together to lock said A-frame members and form a reinforcing panel structure; and means tying the panel structure in one wall to the panel structure in an adjacent connected wall.

15. An A-frame concrete wall reinforcing member comprising generally A-shaped cross rod members, and spaced apart longitudinal rod members, said cross rod members being connected at spaced intervals with said longitudinal rod members, and the ends of said cross rod members being formed with engaging means for engagement with the longitudinal rods of an adjacent A-frame member nested therewith.

16. An A-frame concrete wall reinforcing member comprising generally A-shaped cross rod members and spaced apart longitudinal rod members, said cross rod members being connected at spaced intervals with said longitudinal rod members, and in-turned hook portions at the ends of said cross rod members for engaging the longitudinal rods of an adjacent A-frame member nested therewith.

17. An A-frame concrete wall reinforcing member comprising generally A-shaped cross rod members and spaced apart longitudinal rod members, said cross rod members being formed with a series of bends, certain cross rod members being connected at said bends at spaced intervals with said longitudinal rod members, and said cross rod members terminating in hook portions for engaging the longitudinal rod members of an adjacent A-frame member nested therewith.

18. An A-frame concrete wall reinforcing member comprising generally A-shaped cross rod members and spaced apart longitudinal rod members, each cross rod member being formed with

aligned leg portions, said cross rod members being connected at spaced intervals with said longitudinal rod members, the connections between said longitudinal rod members and each cross rod member being at spaced apart intervals along said aligned leg portions.

19. An A-frame concrete wall reinforcing member comprising a plurality of generally A-shaped cross rod members and a plurality of longitudinal rod members, each cross rod member being formed with an apex from which central V-shaped leg portions extend terminating at bends with out-turned aligned leg portions which terminate at bends with parallel leg portions which terminate in hook means, a plurality of said cross rod members being connected at their apices to one longitudinal rod member, and a plurality of longitudinal rod members being connected with each cross rod member at spaced intervals along said aligned leg portions.

20. An A-frame concrete wall reinforcing member comprising generally A-shaped cross rod members and spaced apart longitudinal rod members, each cross rod member being formed with a central apex from which V-shaped central leg portions extend terminating at bends in out-turned aligned leg portions terminating at bends in parallel leg portions terminating in angularly hooked portions; and said cross rod members being connected at spaced intervals at their apices with one longitudinal rod, at the bends between central and out-turned leg portions with second and third longitudinal rods and at the bends between out-turned and parallel leg portions with fourth and fifth longitudinal rods.
